SURGICAL OPERATING TABLE

Julio Piñeiro Sorondo, Buenos Aires, Argentina

Application January 23, 1941, Serial No. 375,678

5 Claims. (Cl. 311—8)

The present invention relates to operating tables, particularly orthopaedic operating tables, and has for its object to provide a new and improved operating table of simple and compact construction, and capable of being collapsed to a small bulk for ready transport. The particular construction adapted to secure the collapsibility of the table, also permits adjustment of certain planes thereof so as to permit of a better and more convenient accommodation of the patient in certain orthopaedic operations.

A further feature of the present invention, intimately connected with the desirable compactness aforementioned, is the provision of oriented apertures in two superimposed planes of the body portion of the novel table, whereby a plurality of accessory rod-like or tubular members may be detachably secured to the table in inclined or upright positions, said members being adjustable for height and being adapted to have instrumentalities of various kinds as for example pulley blocks, attached thereto.

Another feature of the novel table according to the present invention, lies in the fact that the body portion thereof comprises a top or table portion rigidly connected in spaced relation to a bottom or floor portion to form an open-sided box like structure to one end of which is slidably secured an auxiliary frame adapted to slide lengthwise of said structure and having slidably secured to it an envelope having an upper surface adapted to act as an auxiliary table or extension and sides adapted, in the collapsed position of the novel table, to embrace the sides of said structure and enclose same, whereby the table proper is protected during transit, and is likewise converted into a closed receptacle in which accessories, instruments, the aforesaid members and the like may be packed.

These and other objects and advantages of the present invention will become apparent in the course of the following detailed description of a preferred embodiment thereof.

In the drawings:

Fig. 1 is a side elevation of an improved operating table according to the present invention.

Fig. 2 is a plan view of the table of Fig. 1 with the envelope member removed.

Fig. 3 is a section on the line III—III of Fig. 2.

Fig. 4 is a transverse sectional view of part of the body portion, and

Fig. 5 is a transverse sectional view of the envelope.

With reference to the drawings, the novel orthopaedic operating table according to the

present invention, comprises a body portion 10 consisting of an upper or table member 12 rigidly connected in spaced relation to a composite floor or lower member 14, by short hollow columns 16, 18, said columns 16 being open at the top as shown at 20 in Fig. 2, to receive detachable accessory tubular members (not shown) and at the bottom detachably to receive tubular leg members 22. Tying said columns 16 and 18 together, and assisting in giving rigidity to the body assembly as well as serving to support the table and floor members respectively, are upper and lower frame members 24 and 26 of angle section, the longitudinal members 28 and 30 of which have a plurality of apertures 32 adapted to receive accessory tubular members when it is necessary to place these transversely of the table.

The upper or table member 12 has its corners cut away as shown at 34 Fig. 2, to allow of access to the upper open ends 20 of the columns 16. Said table member 12 has also a plurality of oriented apertures some of which, as for example the aperture 36 centrally disposed near the end of the table member remote from the cut away corners, pass normally through the table member, while others, as for example the pair of apertures 38 symmetrically disposed in the neighborhood of the cut away corners, are cut at an angle to the normal such that they slant downwardly and towards the opposite end of the table member, and others, as for example the three apertures 40, 42 and 44 spaced along the center line of the table member, and two pairs 46, 48 of apertures disposed symmetrically about said center line and near the longitudinal edges of the table member, slope in the reverse direction and still others such as the apertures 50 and 52 which are disposed in pairs aligned with the pairs 46 and 48, the pair 50 coming between pair 46 and the columns 16 and the pair 52 lying between pairs 46 and 48, slope inwardly and downwardly crosswise of the table member. In the example shown two more pairs of apertures are provided in the table member, one of which, 54, is located near the corners remote from the cut away corners 34 and the other, 56 of which is arranged symmetrically about central aperture 44.

The pair of apertures 54 is circular in cross-section as are all the other apertures in the table member so far particularly described, and said apertures 54 slope downwardly and inwardly in a direction approximately diagonal of the table member. The remaining pair 56, are in the shape of truncated rectangular pyramids with the

larger end in the upper surface of said table member and the longitudinal center line normal to the table member. Some of the apertures, as for instance, apertures 40 and 36, may have crossing them a recess 58, 60 adapted to receive a pin (not shown) passing through said accessory tubular members or standards, to limit the penetration thereof through the body portion 10.

In Fig. 3 one accessory tubular member is shown in dotted lines at 62, passing through aperture 42 of the table member and another opening to be hereinafter described. It will be observed that said tubular member 62 has transverse perforations 64 adapted to permit of the passing therethrough of the aforesaid pins.

Such accessory tubular member may be utilized, for example, to sustain a support having a slot therein, into which a plate is adapted to be introduced and secured, said plate being useable as a rigid support for a foot, and being adapted to have a bandage, dressing said foot, also wound round said plate, particularly when the foot has to be put in plaster, whereby cracking of said plaster owing to movements of said foot is avoided, and more especially, said foot is firmly held during the whole time necessary, and it is also possible to disengage the foot from the said plate without breaking the plaster, as for instance for inspection.

Referring now to Figs. 1 and 3, the floor member 14 comprises perforated cross members 66, 68 and 70, the perforations of which are aligned with the perforations of the table member. In Fig. 3 only the perforations 72, 74 and 76 corresponding respectively to the apertures 40, 42 and 44 in the table member, are shown, but it is believed that the general idea of the lay-out will be clear from the foregoing to those skilled in the art.

The floor member 14 further comprises filler members 78 which may be imperforate and of thinner material than the cross members 66, 68 and 7, since said filler members are intended only to complete the flooring, whereas the cross members 66, 68 and 70 likewise serve as intermediate ties for the lower frame member 26.

Parallel with the free, or lower, marginal portion of the upper longitudinal members 28 of the upper frame 24, is an L section guide member 80, which terminates at the end thereof remote from the cut away corners 34 of the table member, in a box portion 82 permanently secured to said longitudinal members 28. Said guide member 80 forms together with the corresponding longitudinal member 28, a slideway for a pair of arms of an extensible auxiliary frame 86, the arms passing through said box portions 82 into said slideway. Said arms 84 are of angle section but their free ends 88 are formed to provide a box like head of rectangular cross section perforated to allow of the insertion of a fixing pin 90 (Fig. 1) when the auxiliary frame is in fully extended position as shown in said Fig. 1, to prevent accidental telescoping of said auxiliary frame into the body portion 10. The end 92 of the frame 86 remote from the heads 88, is likewise of angle section and has pending therefrom a pair of tubular feet 94, adapted to receive detachably at their free ends extension members 96, which are added when the tubular leg members 22 are inserted in the columns 16, 18 of the body portion 10, so that the frame 86 may be supported in parallel relationship to said table member 12.

The upper side of the member 92 has secured to it a central bar 98 and two shorter outer bars

100, spaced from said central bar 98 to form gaps 102 for a purpose to be hereinafter explained. The ends of the shorter bars 100 remote from the central bar 98 are substantially in alignment with the inside edges of the longitudinal members 84 of the frame 86. The object of this arrangement will become clear at a later stage of this description.

Mounted on the auxiliary frame 86 is an envelope or housing 104, having sides 106, a top 108 and having its end remote from the body portion 10 closed by an end wall 110. The housing 104 is therefore open at the bottom and at the end nearest said body portion 10. Across the bottom of the housing 104 and in proximity to the open end, extends a check bar 112 which passes beneath the longitudinal members 84 of frame 86, and thus limits upward movement of the open end of said housing. Downward movement of the housing is limited by longitudinal fins 114 projecting inwardly from the side walls 106 of the housing and adapted to rest slidably on the longitudinal members 84 of frame 86. The ends of said fins 114 nearest the open end of the housing 104, are bent up to form turning shoes 116 and in the proximity of said turning shoes, the fins 114 are provided with claws 118 which extend downwardly past the inner edges of the longitudinal members 84 and limit lateral and upward movement of the housing with respect to the frame 86. The inner edges of the fins 114 are substantially flush with the inner edges of the longitudinal members 84 so that they slidably contact the outer ends of the shorter bars 100 aforementioned.

As best seen in Fig. 2, the longitudinal members 84 of frame 86 are recessed at their junction with the end member 92 to form slots 120 where-through the claws 118 are adapted to be lifted when the housing 104 has been slid away from the body portion as far as possible, that is until the claws 118 abut against the end member 92. The claws 118 are lifted through said slots by raising the closed end 110 of the housing 104 during which movement the open end of the housing turns on the turning shoes 116 which support the weight of said open end by bearing on the longitudinal members 84. When the claws 118 have been lifted through said slots 120, the housing may be slid further away from the body portion 10, while riding on the turning shoes 116, until said turning shoes themselves are clear of the end member 92. The angle of the turning shoes 116 with respect to the fins 114 is such that when the turning shoes 116 are in engagement with the longitudinal members 84, the upper portion of the open end of the housing is almost touching the longitudinal members, so that when the housing has been slid away from the body portion 10 until the turning shoes 116 clear the end member 92 as explained above, the open end of the housing will drop so small an amount as not to cause a damaging bumping thereof against the longitudinal members 84.

When in the circumstances just explained, the closed end of the housing 104 is lowered, the turning shoes 116 and the fins 114 may be passed below the longitudinal members 84 whereby the housing is dropped from the position shown in Fig. 1 and the top 108 is brought in close proximity to said longitudinal members.

Owing to the fact that said longitudinal members or arms 84 are positioned with respect to the table member 12 to be slid therebeneath, it is necessary to provide means for maintaining the

top 108 of the housing, when in its lowered position level with said table member, since said top is then intended to act as an extension of said table member. Said level maintaining means comprise an upper cross member 122 secured to the top 108 of the housing at the open end thereof, and a pair of internal longitudinal ribs 124 attached to the inner face of said top 108 and spaced apart so that when the housing is in its lowered position, said ribs 124 will fit into the gaps 102 between the bars 98 and 100 on the end member 92 of frame 86 thereby providing a second levelling support for said top in any position of the housing relatively to said body portion 10.

The depth of the housing 104 is such that, in its lowered position, and with the frame 86 telescoped into the body portion as previously explained, the housing may just be slid over said body portion to enclose same, the top 108 lying over and protecting the table member 12, the sides 106 covering the otherwise open sides of the body portion 10 and the end 110 closing the corresponding end of said body portion, the opposite end of which may conveniently be provided with a hinged panel indicated in dotted lines at 126 in Fig. 1 so as to complete the closure. When such panel is fitted, abutment members 128 therefore may be provided between the table and the floor members of the body portion as shown in Figs. 1 and 4. When the table is in collapsed position two detachable wooden plane members are located between the table member 12 and the top 108.

From the foregoing it will be seen that by the present invention there has been provided an operating table which can be collapsed into a very compact unit, which, in addition to being readily transportable and particularly suitable for transport where the space factor is a very important consideration, as for example in aircraft, will also serve to contain all the necessary accessories, instrumentalities, instruments, bandages, weights and the like, and can rapidly be set up for use. It also permits of the locating of such accessories as standards, limb supports, tensioning means and the like in the proper positions requisite for most orthopaedic and also some surgical purposes thereby permitting the duplication in the field of a fully equipped modern theater table, with the consequent advantage to the patient and to the surgeon called on to perform emergency operations at places remote from hospitals. Apart from this use of the novel table, it has proved to be of great utility as part of the equipment of an ordinary operating theater, since the readiness with which the ancillary apparatus can be positioned therein and secured thereto, and the fact that the housing top forms an additional surface which can be adjusted lengthwise of the table as a whole and which has an upper and a lower effective position, together with the compactness and relatively low cost of the novel table, make it useable not only as a means for holding a patient in a particular position for an extended period of time, as in the treatment of fractures, but also as an actual operating table.

While a preferred embodiment of the present invention has been described in detail it is not intended to limit the scope of the present invention thereto, but only as it is defined in the appended claims, as it is clear that various structural and other modifications may be made therein without departing from the nature of the present invention.

I claim:

1. An orthopaedic operating table, comprising a body portion including a top table portion, a floor portion, hollow tubular columns rigidly securing said floor portion to said table portion in spaced relationship to provide a box like structure, guide means extending longitudinally of said body portion below said top portion, an auxiliary frame having a pair of longitudinal side members, an end member joining the side members at one of their ends in parallel spaced relationship, the other ends of said side members being slidably engaged in said guide means, a pair of hollow tubular members depending from said end member and an envelope mounted on said auxiliary frame, said envelope comprising a pair of side walls, a top and an end wall, supporting means on said side walls adapted to support the envelope in an upper position on said side members, means operatively associated with said side members for maintaining said envelope in its upper position, disengagement means operatively associated with said maintaining means, whereby said maintaining means may be disengaged from said side members, and said envelope be moved into a lower position, said columns and said depending members being adapted detachably to receive extension members to support said operating table at variable heights.

2. An orthopaedic operating table comprising a body portion including a table portion, a floor portion, hollow tubular columns rigidly securing said floor portion below the table portion in spaced relationship, in said table portion having a plurality of apertures therein the axes of which are oriented, said floor portion having a plurality of apertures corresponding to those in the table portion and the axes of which are oriented, corresponding apertures in the table and floor portions having their axes aligned for the insertion of instrumentalities in oriented relationship to the plane of said table portion, upper and lower perforated frame members secured to said columns and supporting said table and said floor portions, guide means extending longitudinally of said body portion below said table portion, an auxiliary frame having a pair of longitudinal side members, an end member joining the side members at one of their ends in parallel spaced relationship, the ends of the side members remote from said end member slidably engaging said guide means whereby said frame may be telescoped with respect to said body portion, an envelope mounted on said auxiliary frame and comprising a pair of side walls, a top and an end wall, supporting means for supporting said envelope on said frame in an upper position in which said top lies in a plane parallel to the plane of the table portion but spaced therefrom on the side thereof remote from the floor portion, secondary supporting means for supporting said envelope on said frame in a lower position in which said top will be substantially co-planar with said table portion, said envelope being adapted when said frame is telescoped with respect to said body portion and said envelope is in the lower position, to enclose said body portion to form therewith a compact unit for transport.

3. A collapsible operating table especially for orthopaedic purposes, comprising a body portion including a table portion, a floor portion, hollow columns rigidly connecting said table portion to said floor portion in parallel spaced relationship to form a box like structure with open sides and ends, upper and lower frame members including apertured side members, tying said columns and

supporting said table and said floor portions, an auxiliary frame slidably coupled to said body portion and adapted to be telescoped with respect thereto beneath said table portion, said auxiliary frame including a pair of longitudinal members the ends thereof remote from said body portion being rigidly joined together by an end member, a plurality of bars secured to said end member and spaced to provide parallel gaps, a slot in each longitudinal member at its point of junction with the end member, an envelope mounted on said auxiliary frame and comprising side walls, a top and an end wall defining a bottomless housing open at the end nearest said body portion, fins extending inwardly from said side walls and adapted to slidably engage said longitudinal members, claw members projecting from said fins and adapted slidably to engage said longitudinal members, the ends of said fins remote from said end wall being upturned to provide a turning shoe, ribs extending longitudinally inside said top in alignment with said gaps, whereby said envelope is supported on said auxiliary frame in an upper position in which said fins and said claws engage said longitudinal members and may be disengaged therefrom by passing said claws through said slots, to bring said envelope into a lower position in which said ribs engage said gaps and said top is substantially co-planar with the table portion.

4. A collapsible operating table especially for orthopaedic purposes, comprising a body portion including a table portion, a floor portion, hollow columns rigidly connecting said table portion to said floor portion in parallel spaced relationship to form a box like structure with open sides and ends, upper and lower frame members including apertured side members, tying said columns and supporting said table and said floor portions, an auxiliary frame slidably coupled to said body portion and adapted to be telescoped with respect thereto beneath said table portion, said auxiliary frame including a pair of longitudinal members the ends thereof remote from said body portion

being rigidly joined together by an end member, a plurality of bars secured to said end member and spaced to provide parallel gaps, an envelope mounted on said auxiliary frame and comprising side walls, a top and an end wall defining a bottomless housing open at the end nearest said body portion, ribs extending longitudinally inside said top in alignment with said gaps, and engaging said end member in said gaps to support the top of said envelope coplanarly with the table portion.

5. A collapsible operating table especially for orthopaedic purposes, comprising a body portion including a table portion, a floor portion, hollow columns rigidly connecting said table portion to said floor portion in parallel spaced relationship to form a box like structure with open sides and ends, upper and lower frame members including apertured side members, tying said columns and supporting said table and said floor portions, an auxiliary frame slidably coupled to said body portion and adapted to be telescoped with respect thereto beneath said table portion, said auxiliary frame including a pair of longitudinal members the ends thereof remote from said body portion being rigidly joined together by an end member, a slot in each longitudinal member at its point of junction with the end member, an envelope mounted on said auxiliary frame and comprising side walls, a top and an end wall defining a bottomless housing open at the end nearest said body portion, fins extending inwardly from said side walls and adapted to slidably engage said longitudinal members, claw members projecting from said fins and adapted slidably to engage said longitudinal members, the ends of said fins remote from said end wall being upturned to provide a turning shoe, whereby said envelope is supported on said auxiliary frame in an upper position in which said fins and said claws engage said longitudinal members and may be disengaged therefrom by passing said claws through said slots.

JULIO PIÑEIRO SORONDO.
